CLAIM

The ornamental design for an insufflation circuit and filter, as shown and described.

DESCRIPTION

FIG. 1 is a top, front and right side perspective view of an insufflation circuit and filter embodying our new design. FIG. 2 is a bottom, rear and left side perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof.

FIG. 8 is a left side view thereof; and,

FIG. 9 is a bottom view of detail 9, identified in FIG. 6. The broken line showing of parts of the drawings is included to illustrate features of the insufflation circuit and filter that form no part of the claimed design.

1 Claim, 4 Drawing Sheets
